(57) **CLAIM**

The ornamental design for a nail lamp, as shown and described.

DESCRIPTION

FIG. 1 is a top, front, left-side perspective view of a nail lamp showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a perspective view thereof in a bended configuration.

The broken lines shown in the drawings depict portions of the nail lamp that form no part of the claimed design.

1 Claim, 8 Drawing Sheets
